UNITED STATES PATENT OFFICE.

OLIVER S. BOWMAN, OF COLORADO SPRINGS, COLORADO.

WINDOW.

Application filed January 3, 1924. Serial No. 684,221.

To all whom it may concern:

Be it known that I, OLIVER S. BOWMAN, a citizen of the United States, and a resident of Colorado Springs, in the county of El

5 Paso and State of Colorado, have invented a new and useful Window, of which the following is a specification.

My invention relates to windows of the rocking type and has for its object the provision of a window of this type having sashes which are adjustable, lockable and removable. Other objects will appear as the description progresses.

Figure 1 represents a front elevation of 15 my window with both sashes closed; Fig. 2, an elevation of a section on the line A—B of Fig. 1; Fig. 3, a plan view of a section on the line C—D of Fig. 1; Fig. 4, a side and an end elevation of the screws 14 and 20 15 in their cooperative positions, drawn to an enlarged scale (as are the remaining Figures); Fig. 5, a side and an end elevation of the screw 15; Fig. 6, two side elevations of the screw 14; Fig. 7, side elevations 25 of the screws 4 and 6; Fig. 8, a fragmentary sectional elevation showing the manner of mounting the lower sash 5; Fig. 9, an elevation of a section on the line E—F of Fig. 8; Fig. 10, an end and a side elevation of 30 the plate 10; Fig. 11, a fragmentary sectional view showing the manner of mounting screws 14 and 15; Fig. 12, a fragmentary sectional plan view showing the manner in 35 which the thumb screw 12 engages the depressions in the plate 10.

The invention comprises a window frame 1, having a sill 2 with a rectangular ridge 3, and screws 4, with convex ends, screwed into said sill; a lower sash 5 having screws 40 6, with concave ends, screwed into the bottom of its lower rail mounted on the convex ends of screws 4 in the manner shown 45 in Figs. 8 and 9; plates 10, with depressions 11, mortised in the jambs of said frame as shown in Figs. 1, 2, 3 and 12; thumb screws 12 screwed thru the side rails of said sash 5 and into the concave depressions 11 of plate 10, as shown in Fig. 12; an upper sash 13 having screws 14, with 50 tongued ends 14^a, screwed into the bottom of its lower rail and mounted on screws 15, having bifurcated ends 15^a, screwed into the jambs of said frame, as shown in detail in Fig. 11; plates 10^b, similar to plates 10, mortised in said jambs; thumb screws 12^a, similar to thumb screws 12, screwed

thru the side rails of sash 13 in the same manner as shown in Fig. 12; stops 16, having triangular beads 16^a, mounted on said jambs.

When the sashes are closed, the triangular beads 16^a fit into longitudinal V grooves in the side rails of both sashes, and the flange 17 fits in front of the rectangular ridge 3, and thereby prevents wind, rain or dust from passing between the side rails and the jambs, or the bottom rail of the lower sash and the sill of said frame.

The lower sash 5 may be adjusted in its relation to the upper sash 13 and trued in its relation to the jambs by means of screws 4 and 5, which also form hinges upon which the lower sash rocks.

The upper sash 13 may be adjusted vertically and horizontally by means of screws 14 and 15, respectively, which also form the hinges upon which said upper sash rocks.

The sashes are locked at any angle, by screwing thumb screws 12 and 12^a until the convex ends enter the concave depressions 11^a in plates 10^a. For convenience, the thumb screws thru the right hand side rails are threaded right hand and those thru the left hand rail are threaded left hand.

The construction of the screws 4 and 6, and of the screws 14 and 15 permits the sashes to be removed.

I claim:

1. In a window of the class described including in combination, a window frame having screws, with convex ends, in the sill, and screws, with bifurcated ends, in the jambs; a window sash having screws, with concave ends, in its lower rail, mounted on the convex ends of said screws in said sill; and a window sash having screws, each having a tongued end, in its bottom rail, mounted on the bifurcated ends of said screws in said jambs; for the purposes set forth.

2. In a window of the class described including in combination, a window frame having screws, with bifurcated ends, in the jambs thereof; and a window sash having screws, each having a tongued end, in its bottom, mounted on the bifurcated ends of 105 said screws in said jamb; for the purposes set forth.

3. In a window of the class described including in combination, a window frame having screws, with convex ends, in the sill, screws, with bifurcated ends, in, and plates, with depressions, on the jambs there-

of; a window sash having screws, with concave ends, in its lower rail, mounted on the convex ends of said screws in said sill, and thumb screws extending thru the side rails 5 thereof and into the depressions in said plates; a window sash having screws, each having a tongued end, in its bottom, mounted on the bifurcated ends of said screws in said jambs, and thumb screws extending 10 thru its side rails and into the depressions in said plates; for the purposes set forth.

4. In a window of the class described including in combination, a window frame having screws, with bifurcated ends, in, and 15 plates, with depressions, on the jambs thereof; a window sash having screws, each having a tongued end, in its bottom, mounted on the bifurcated ends of said screws in said jambs, and thumb screws extending 20 thru its side rails and into the depressions in said plates; for the purposes set forth.

5. In a window of the class described including in combination, a window frame having screws, with bifurcated ends in, and 25 plates, with depressions on the jambs thereof; triangular beaded stops, mounted on said jambs; a window sash having screws, each having a tongued end in its bottom, mounted on the bifurcated ends of said screws in 30 said jambs, thumb screws extending thru its side rails and into the depressions in said plates, and V grooves in its side rails fitting over the triangular beads on said stops; for the purposes set forth.

35 6. In a window of the class described in combination, a window frame having screws, with convex ends in the sill screws with bifurcated ends, in, and triangular beaded stops on the jambs thereof; a window sash 40 having V grooves in its side rails and screws, with concave ends, in its bottom, mounted on the convex ends of said screws in said sill, said V grooves fitting over the triangular beads on said stops; and a window 45 sash, having screws each having a tongued end in its bottom, mounted on the bifurcated ends of said screws in said jambs, and V grooves in its side rails fitting over the triangular beads on said stops; for the 50 purposes set forth.

7. In a window of the class described, in combination, a frame having a rectangular ridge on its sill; screws, with convex ends, in said ridge; a sash, having a downwardly 55 extending flange on, and screws, with concave ends, in the lower rail thereof, mounted on said screws in said ridge; for the purposes set forth;

60 8. In a window of the class described, in combination, a frame having a rectangular ridge on its sill; screws, with convex ends, in said ridge; a sash having a downwardly extending flange on, and screws, with concave 65 ends, in the lower rail thereof, mounted on said screws in said ridge; screws, with bifur-

cated ends, in the jambs of said frame; and a sash, having screws, each having a tongued end, in its bottom rail, disposed in said frame, with the tongued ends of said screws disposed between the bifurcated ends 70 of said screws in said jambs; for the purposes set forth.

9. In a window of the class described, in combination, a window frame having a rectangular ridge on its sill; screws, with bifurcated ends, in the jambs of said frame; and a sash having screws, each having a tongued end, in its bottom rail, disposed in said frame, with the tongued ends of said screws disposed between the bifurcated ends of said 75 screws in said jambs; for the purposes set forth.

10. In a window of the class described, in combination, a window frame; screws, with bifurcated ends, in the jambs of said frame; a sash, having screws, each having a tongued end, in its bottom rail, disposed in said frame, with the tongued ends of said screws disposed between the bifurcated ends of said 80 screws in said jambs; for the purposes set forth.

11. In a window of the class described, in combination, a window frame; screws, with bifurcated ends, in the jambs of said frame; a sash, having screws, each having a tongued end, in its bottom rail, disposed in said frame, with the tongued ends of said screws disposed between the bifurcated ends of said 85 screws in said jambs; plates, having flanges thereon, mounted on the jambs of said frame; and thumb screws, with convex ends, screwed thru the side rails of said sash and against said plates; for the purposes set forth.

12. In a window of the class described, in combination, a window frame; screws, with bifurcated ends, in the jambs of said frame; a sash, having screws, with tongued ends, in its bottom rail, disposed in said frame, each having a tongued end of said screws disposed between the bifurcated ends of said 95 screws in said jamb; plates, having concave depressions therein and flanges thereon, mounted on said jambs; and thumb screws, having convex ends, screwed thru the side rails of said sash and into the concave depressions in said plates; for the purposes set forth.

13. In a window of the class described, in combination, a window frame; screws, with bifurcated ends, in the jambs of said frame; a sash, having screws, each having a tongued end, in the bottom of its lower rail, disposed in said frame, with the tongued ends of said screws disposed between the bifurcated ends of said screws in said jambs; plates mounted on said jambs; and thumb screws, having convex ends, screwed thru the side rails of said sash and against said plates; for the 105 purposes set forth.

OLIVER S. BOWMAN.
